ABSTRACT OF THE DISCLOSURE

The present invention provides the pentacosapeptides of general formula D-seryl-L-tyrosyl-L-seryl-L-norleucyl-X - L - histidyl - L - phenylalanyl - L - arginyl - L-tryptophanyl - glycyl - L - lysyl - L - proyl - L - valyl-glycyl-L - lysyl - L - lysyl - L - lysyl - L - lysyl - L - proyl-L-valyl - L - lysyl - L - valyl - L - tyrosyl-L-proyl-L-valinamide, in which X signifies an L-glutamyl or L-glutaminyl radical, their therapeutically active acid addition salts and heavy metal complexes. The pentacosapeptides of the above formula, their salts and heavy metal complexes exhibit a high adrenocorticotrophic effect. The production of these peptides is furthermore described.

The present invention relates to new polypeptides and a process for their production.

The present invention provides the pentacosapeptides of general formula D-seryl-L-tyrosyl-L-seryl-L-norleucyl-X - L - histidyl - L - phenylalanyl - L - arginyl-L-tryptophanyl - glycyl - L - lysyl - L - proyl - L - valyl-glycyl-L-lysyl - L - lysyl - L - lysyl - L - lysyl - L - proyl-L-valyl-L-lysyl - L - valyl - L - tyrosyl - L - proyl-L-valinamide, in which X signifies an L-glutamyl or L-glutaminyl radical, their therapeutically active acid addition salts and heavy metal complexes. The pentacosapeptides of the above formula, their salts and heavy metal complexes exhibit a high adrenocorticotrophic effect. The pentacosapeptides of the above formula are hereinafter named as follows: D - Ser¹ - Nle⁴ - Lys¹⁷ - Lys¹⁸ - Val-NH₂²⁵-pentacosapeptide and D - Ser¹-Nle⁴-Gln⁵-Lys¹⁷-Lys¹⁸-Val-NH₂²⁵-pentacosapeptide.

The pentacosapeptide of formula L-seryl-L-tyrosyl-L-seryl - L - norleucyl - L - glutamyl - L - histidyl - L - phenylalanyl - L - arginyl - L - tryptophanyl-glycyl-L-lysyl - L - proyl - L - valyl - glycyl - L - lysyl - L - lysyl - L - proyl - L - valyl - L - lysyl - L - valyl - L - tyrosyl - L - proyl - L - valinamide, having a corticotrophic effect and hereinafter named Nle⁴-Lys¹⁷-Lys¹⁸-Val-NH₂²⁵-pentacosapeptide, is known.

An advantage of Nle⁴-Lys¹⁷-Lys¹⁸-Val-NH₂²⁵-pentacosapeptide over natural ACTH is that the former has no antigenic effects. A further advantage is that it is devoid of a methionine radical in the 4-position, which methionine radical is easily oxidized whereby the hormone becomes inactive; Nle⁴ - Lys¹⁷-Lys¹⁸-Val-NH₂²⁵-pentacosapeptide contains a norleucine radical in place of the methionine radical present in ACTH, which norleucine radical has the same steric properties as the methionine radical, but is stable to oxidation. Furthermore, Nle⁴-Lys¹⁷-Lys¹⁸-Val-NH₂²⁵-pentacosapeptide has two lysine radicals in the 17- and 18-positions in place of the arginine radicals present in these positions in natural ACTH. This simplifies the synthetic production of Nle⁴-Lys¹⁷-Lys¹⁸-Val-NH₂²⁵-pentacosapeptide and, surprisingly, no lowering of the biological activity has been ascertained in the new compound.

Furthermore, Nle⁴ - Lys¹⁷ - Lys¹⁸ - Val-NH₂²⁵-pentacosapeptide has a valinamide radical in the 25-position,

2

which is not present in this position in natural ACTH. This valinamide radical protects the peptide chain from enzymatic degradation. Despite these advantages of Nle⁴-Lys¹⁷ - Lys¹⁸ - Val-NH₂²⁵-pentacosapeptide over natural ACTH, this compound has the disadvantage that it is easily affected by aminopeptidase degradation.

In accordance with the present invention, compounds having all the advantages of Nle⁴-Lys¹⁷-Lys¹⁸-Val-NH₂²⁵ but which are not affected by aminopeptidases have been produced. This has been achieved by replacing the terminal L-serine radical of Nle⁴ - Lys¹⁷ - Lys¹⁸-Val-NH₂²⁵-pentacosapeptide by a D-serine radical yielding D-ser¹-Nle⁴ - Lys¹⁷ - Lys¹⁸ - Val-NH₂²⁵-pentacosapeptide. As D-amino acid radicals are not found in the natural, biologically active peptide hormones, it was not to be expected that the replacement of a natural amino acid radical by an antipode not occurring in nature would result in a compound having biological and therapeutical properties not only qualitatively equal but also quantitatively superior to those of natural ACTH. The other compound of the invention has been produced by replacing the glutaminic acid radical in the 5-position of D-ser¹-Nle⁴-Lys¹⁷ - Lys¹⁸ - Val - NH₂²⁵ - pentacosapeptide by a glutamine radical. Surprisingly this may be done without a loss of the biological activity so that D-ser¹-Nle⁴-Gln⁵-Lys¹⁷ - Lys¹⁸ - Val - NH₂²⁵-pentacosapeptide has all the advantages of D - ser¹ - Nle⁴ - Lys¹⁷ - Lys¹⁸-Val-NH₂²⁵-cosapeptide.

The pentacosapeptides of the invention may be produced by methods for the synthesis of compounds of this type in actual use of described in the literature on the subject, it being possible to join together the amino acids in the order indicated in the above formula one at a time or by first forming constituent peptide units and joining these together.

One method of producing the pentacosapeptides of the invention consists in that L-valyl-glycyl- ϵ -N-R-L-lysyl- ϵ -N-R-L-lysyl- ϵ -N-R-L-lysyl - proyl-L-valyl- ϵ -N-R-L-lysyl-L-valyl-L-tyrosyl-L-proyl-L-valinamide, in which R signifies a carbo-tert-butoxy or carbo-tert-amyoxy radical, is condensed with N-triphenylmethyl-L-glutaminyl (or γ -O-tert-butyl-L-glutamyl) - Im - triphenylmethyl-L-histidyl-L-phenylalanyl-L-arginyl - L - tryptophanyl-glycyl- ϵ -N-R-L-lysyl - L - proline-2,4,5-trichlorophenyl-ester, in which R has the above significance, the resulting N-triphenylmethyl-L-glutaminyl (or γ -O-tert-butyl-L-glutamyl)-Im-triphenylmethyl - L - histidyl - L-phenylalanyl-L-arginyl - L - triptophanyl-glycyl- ϵ -N-R-L-lysyl-L-prolyl - L - valyl - glycyl- ϵ -N-R-L-lysyl- ϵ -N-R-L-lysyl - L - proyl-L-valyl- ϵ -N-R-L-lysyl-L-tyrosyl-L-proyl-L - valinamide, in which R has the above significance, is condensed with N-R'-D-seryl-L-tyrosyl-L-seryl-L-norleucylazide, in which R' signifies a triphenylmethyl, a carbo-tert-butoxy or a carbo-tert-amyoxy radical, after removal of the N-triphenylmethyl radical of the glutaminyl (or γ -O-tert-butyl-L-glutamyl) radical, and all the protective radicals of the resulting new, protected pentacosapeptides N-R'-D-seryl-L-tyrosyl-L-seryl-L-norleucyl - L - glutamyl (or γ -O-tert-butyl-L-glutamyl)-Im-triphenylmethyl - L - histidyl-L-phenylalanyl-L-arginyl - L - triptophanyl-glycyl- ϵ -N-R-L-lysyl-L-proyl-L-valyl-glycyl - ϵ - N - R-L-lysyl- ϵ -N-R-L-lysyl- ϵ -N-R-L-lysyl - L - prolyl - I - valyl- ϵ -N-R-L-lysyl-L-tyrosyl-L-proyl - L - valinamide, in which R and R' have the above significance, are removed in one or more stages in an acid medium.

The starting materials for producing the pentacosapeptides of the invention, insofar as they were hitherto unknown, may be obtained by methods for the synthesis of peptides in actual use or described in the literature, it being possible to join together the amino acids one

at a time or by first forming constituent peptide units and joining these together.

It should be noted that the pentacosapeptides of the invention may likewise be obtained or used in the form of their salts. Examples of acids for acid addition salt formation are: acetic, propionic, glycolic, lactic, pyruvic, malonic, succinic, maleic, fumaric, tartaric, citric, benzoic, cinnamic, salicylic, 2-phenoxy- or 2-acetoxy-benzoic, mandelic, methanesulphonic, ethanesulphonic, hydroxyethanesulphonic, benzene- or toluenesulphonic, naphthalenesulphonic and sulphamic acid, polymeric acids, e.g. tannic, alginic or polygalacturonic acid, polyphloretinic phosphate or carboxymethyl cellulose, and halogen hydracids, e.g. hydrochloric or hydrobromic acid, nitric, thiocyanic, sulphuric and phosphoric acid. Zinc may, for example, be used for the heavy metal complex.

A major advantage of the synthetic pentacosapeptides over the natural hormone extracted from animal material is that the former have no antigenic effects. Absence of antigenic effect in a substance indicates no objection to its use even in the face of an earlier allergic reaction to natural ACTH.

According to the usual and accepted standard tests the pentacosapeptides of the invention have the following biological activity:

570±140 corticotropin IU for every mg. of D-Ser¹-Nle⁴-Lys¹⁷-Lys¹⁸-Val-NH₂²⁵-pentacosapeptide
550±140 corticotropin IU for every mg. of D-Ser¹-Nle⁴-Gln⁵-Lys¹⁷-Lys¹⁸-Val-NH₂²⁵-pentacosapeptide.

The pentacosapeptides of the invention were tested in accordance with the third International Standard for corticotropin which is available in the form of an "International Standard for Corticotropin" and permits the standardization of ACTH preparations in International Units.

It has been found that, upon intravenous administration, the new pentacosapeptides have a longer duration of action than the hitherto known naturally occurring and synthetic ACTH compounds.

The surprisingly high activity of the new pentacosapeptides, which was ascertained upon standardization, has been confirmed upon therapeutic application, so that on a weight basis the new pentacosapeptides are more active than all the hitherto known naturally occurring and synthetic ACTH preparations.

The dose of the pentacosapeptides of the invention ranges between about 40 and 60 IU daily, in exceptional cases between 10 and 100 IU daily.

The pentacosapeptides of the invention may be used as medicaments, for example in the form of pharmaceutical preparations. These may contain the said compounds in mixture with an organic or inorganic carrier material

Production of H-D-Ser-Tyr-Ser-Nle-Glu(R₂)-His-Phe-Arg-Try-Gly-Lys-Pro-Val-Gly-Lys-Lys-Lys-Pro-Val-Lys-Val-Tyr-Pro-Val-NH₂

R=NH₂ or OTB
R₂=NH₂ or OH

which is suitable for parenteral administration. Appropriate carrier materials are substances which do not react with the new compounds, e.g. gelatin, lactose, starch, magnesium stearate, talcum, vegetable oils, benzyl alcohols, gum arabic, polyalkylene glycols, vaseline, cholesterol and other known pharmaceutical carrier materials. The pharmaceutical preparations may, for example, be used in the liquid form as solutions, suspensions or emulsions. They may be sterilized and/or they may contain adjuvants, such as preserving, stabilizing, wetting or emulsifying agents. However, they may contain other therapeutically valuable substances. The new compounds may also be administered in the form of depot preparations as is the case with natural ACTH.

Examples of radicals for blocking the amino radical of the serine radical during the synthesis of the new pentacosapeptides are the triphenylmethyl, the carbo-tert-butoxy and the carbo-tert-amyloxy radical, but other suitable protective radicals, e.g. the carbobenzoxy, the trifluoroacetyl, the acetyl, the chloroacetyl and the formyl radical, may likewise be used.

Suitable radicals for blocking the ϵ -amino radical of the lysine radical are the carbo-tert-butoxy and the carbo-tert-amyloxy radical, but other suitable protective radicals, e.g. the carbobenzoxy, toluenesulphonyl, phthalyl, formyl and trifluoroacetyl radical, may likewise be used.

A suitable radical for blocking the γ -carboxyl radical of the glutaminic acid radical is the tert-butoxy radical, but other suitable protective radicals, e.g. the methoxy, the ethoxy, the tert-amyloxy, the amide or the benzyloxy radical, may likewise be used.

A suitable radical for the blocking of the imidazole radical of the histidine radical is the triphenylmethyl radical, but other suitable protective radicals, e.g. the carbo-tert-butoxy, carbo-tert-amyloxy, carbobenzoxy or benzyl radical, may likewise be used.

The following abbreviations are used in the text and in the drawings:

CBO=carbobenzoxy	Gly=glycyl
Trit=trityl=triphenylmethyl	His=L-histidyl
CTB=carbo-tert-butoxy	Lys=L-lysyl
NO ₂ =nitro	Nle=L-norleucyl
OCP=2,4,5-trichlorophenoxy	Phe=L-phenylalanyl
OTB=tert-butoxy	Pro=L-prolyl
OMe=methoxy	Ser=L-seryl
OEt=ethoxy	D-Ser=D-seryl
Arg=L-arginyl	Try=L-tryptophanyl
Glut=L-glutamyl	Tyr=L-tyrosyl
Gln=L-glutamyl	Val=L-valyl
	Im=imidazolyl

In the following non-limitative examples all temperatures are indicated in degrees centigrade.

5
EXAMPLE 1

Carbo - tert - butoxy - D - seryl - L - tyrosyl - L - seryl - L - norleucine hydrazide. (CTB - D - Ser - Tyr - Ser-Nle-NHNH₂)

54 g. of H-Ser-Nle-OMe·HCl and 63 g. of CBO-Tyr-OH are dissolved in 860 ml. of acetonitrile, cooling is effected to 0°, 28 ml. of triethylamine are added, cooling is effected to -10° and 41 g. of dicyclohexyl carbodiimide are added. The mixture is stirred at 0° for 16 hours and is then filtered. The precipitate is washed with 1400 ml. of pyridine. The combined filtrates are evaporated and the residue crystallized from ethyl acetate. 101 g. of CBO - Tyr - Ser - Nle - OMe (melting point 140-142°, $[\alpha]_D^{20} = -15^\circ$ in dimethyl formamide) are obtained. 51 g. of the product obtained above are dissolved in 2 litres of a 1 N solution of hydrochloric acid in methanol and hydrogenation is effected in the presence of 10 g. of palladium/charcoal. After about 2 hours hydrogen is no longer taken up. Filtration and evaporation are effected and the residue is crystallized from a mixture of methanol and ether (3:1). 42 g. of H-Tyr-Ser-Nle-OMe·HCl, having a melting point of 227°, $[\alpha]_D^{20} = -7^\circ$ in dimethyl formamide, are obtained.

60 g. of D-serine methyl ester hydrochloride are dissolved in 200 ml. of dimethyl formamide and 54 ml. of triethylamine, cooling is effected to 0° and the triethylamine hydrochloride is filtered off. Dimethyl formamide is evaporated in a high vacuum and the residue dissolved in 150 ml. of pyridine. 100 g. of tert-butyl-oxy-carbonyl azide are added dropwise and the mixture is allowed to stand at 20° for 2 days. The solvent is evaporated and the product is taken up in ethyl acetate. After washing with water, dilute hydrochloric acid and potassium bicarbonate solution, drying is effected over sodium sulphate. After evaporating the ethyl acetate CTB-D-Ser-OMe results as an oil. The ester is dissolved in 500 ml. of methanol and is allowed to stand at 20° with 50 ml. of hydrazine hydrate for 2 days. After evaporating the methanol, the hydrazide crystallizes. After recrystallization from hot ethyl acetate, 53 g. of CTB-D-Ser-NHNH₂, having a melting point of 114°, $[\alpha]_D^{21} = -3^\circ$ in dimethyl formamide, are obtained. 10 g. of CTB-D-serine hydrazide are dissolved at -10° in 136 ml. of 1 N hydrochloric acid containing 15 g. of sodium chloride. 160 ml. of ethyl acetate and subsequently 3.8 g. of sodium nitrite are added in 3 portions at the same temperature. The mixture is allowed to react for a further 5 minutes at -10° whilst stirring continuously. The ethyl acetate phase is separated, washed with a cold 10% potassium bicarbonate solution and dried with sodium sulphate. A solution of 13 g. of H-Tyr-Ser-Nle-OMe hydrochloride in 60 ml. of dimethyl formamide and 6 ml. of triethylamine is added to the dried solution. The ethyl acetate is subsequently evaporated in a vacuum and the solution allowed to stand at 20° for 16 hours. The remaining solvent is evaporated in a vacuum and the residue dissolved in ethyl acetate. Washing with dilute phosphoric acid and potassium bicarbonate solution and drying over sodium sulphate are effected. After evaporating the solvent and precipitating with ether 15 g. of CTB-D-Ser-Tyr-Ser-Nle-OMe, having a melting point of 135°, $[\alpha]_D^{20} = -6^\circ$ in methanol, are obtained. 11 g. of CTB-D-Ser-Tyr-Ser-Nle-OMe are dissolved in 100 ml. of methanol and 4.5 ml. of hydrazine hydrate are added. The mixture is allowed to stand over night at 20°, whereupon the product crystallizes. Filtration and washing with methanol and petroleum ether are effected. 7.7 g. of CTB-D-Ser-Tyr-Ser-Nle-hydrazide, having a melting point of 210°, $[\alpha]_D^{20} = +6.4^\circ$ in dimethyl formamide, are obtained.

6
EXAMPLE 2

D - seryl - L - tyrosyl - L - seryl-L-norleucyl-L-glutamyl-L-histidyl - L - phenylalanyl - L - arginyl-L-tryptophanyl-glycyl - L - lysyl - L - prolyl - L - valyl-glycyl-L-lysyl-L-lysyl - L - lysyl - L - lysyl - L - prolyl-L-valyl-L-lysyl-L-valyl - L - tyrosyl-L-prolyl-L-valinamide. (H-D-Ser-Tyr-Ser - Nle - Glu - His - Phe - Arg - Try-Gly-Lys-Pro-Val-Gly - Lys - Lys - Lys - Lys - Pro-Val-Lys-Val-Tyr-Pro-Val-NH₂)

5 2.0 g. of CTB-D-Ser-Tyr-Ser-Nle-NHNH₂ (Example 1) are dissolved in 12 ml. of dimethyl formamide, 4 ml. of water are added, cooling is effected to -10°, 2 ml. of 6 N hydrochloric acid and subsequently 280 mg. of sodium nitrite are added, stirring is effected at -5° for 5 minutes, 300 ml. of 0.2 N potassium bicarbonate solution are added and the mixture is centrifuged. The resulting CTB-D-Ser-Tyr-Ser-Nle-N₃ is dissolved in 50 ml. of dimethyl formamide, 10.5 g. of H-Glu(OTB)-(Trit) His-Phe-Arg-Try-Gly-(CTB)Lys-Pro-Val - Gly - (CTB)Lys-(CTB)Lys-(CTB)Lys-Pro - Val - (CTB)Lys-Val-Tyr-Pro-Val-NH₂ acetate are added, the mixture is allowed to stand at 0° for 12 hours, a further amount of tetrapeptide azide produced from 2.0 g. of CTB-D-Ser-Tyr-Ser-Nle-NHNH₂ is added, the mixture is allowed to stand at 0° for 6 hours, is evaporated, treated with ethyl acetate, washed with hot acetone and ethyl acetate and dried in a vacuum. The resulting product is dissolved in 100 ml. of 90% trifluoroacetic acid, the solution is allowed to stand at 20° in an atmosphere of nitrogen for one hour, is evaporated, treated with ethyl acetate, filtered and dried. The resulting product is dissolved in 500 ml. of Amberlite IRA-410 in the acetate form, is filtered and lyophilized. After drying over sodium hydroxide, 7.3 g. of H - D-Ser-Tyr-Ser-Nle-Glu-His-Phe-Arg-Try-Gly-Lys-Pro-Val-Gly-Lys-Lys-Pro-Val-Lys-Val-Tyr - Pro-Val-NH₂ heptaacetate decahydrate, having a homogeneous behaviour in chromatography and electrophoresis, are obtained. (Total hydrolysis gives the following composition of amino acids:

Ser_{1.9}Tyr_{1.9}Nle_{1.0}Glu_{1.0}His_{0.9}Phe_{1.1}Arg_{1.1}Gly_{2.0}Lys_{6.1}Pro_{3.0}Val_{3.9})

Microanalysis.—Calculated (percent): C, 52.6; H, 7.6; N, 14.9; O, 24.7. Found (percent): C, 52.4; H, 7.5; N, 15.0; O, 24.8. Melting point 202° with decomposition, $[\alpha]_D^{20} = -82^\circ$ in 1 N acetic acid.

EXAMPLE 3

50 Trityl-L-glutamyl-Im-trityl - L - histidyl - L - phenylalanyl-L-arginyl - L - tryptophanyl-glycyl-e-N-carbo-tert-butoxy - L - lysyl-L-proline-2,4,5-trichlorophenyl ester. (Trit - Gln-(Trit)His-Phe-Arg-Try-Gly-(CTB)Lys-Pro-OCP)

55 457 g. of H-His-Phe-OMe·2 HBr and 266 ml. of triethylamine are dissolved in 1000 ml. of dimethyl formamide, stirring is effected at 0° for 10 minutes, filtration is effected, 445 g. of CBO-Gln-OCP are added to the filtrate and the mixture is allowed to stand at 20° for 16 hours. The dimethyl formamide is removed by evaporation, the residue is dissolved in ethyl acetate, washed with dilute acetic acid/water and a 1 N sodium bicarbonate solution. Drying over sodium sulphate and evaporation are effected and the residue is crystallized from ethyl acetate. 328 g. of CBO-Gln-His-Phe-OMe, having a melting point of 195°, $[\alpha]_D^{20} = -20^\circ$ in dimethyl formamide, are obtained.

The tripeptide obtained above is dissolved in 3 litres of methanol, hydrogenation is effected in the presence of 50 g. of 10% palladium/charcoal, filtration and evaporation are effected, the residue is dissolved in 1.5 litres of methylene chloride, cooling is effected to 0°, 140 ml. of triethylamine and then 270 g. of triphenylchloromethane are added, the mixture is allowed to stand at 20° for 16 hours, washing is effected with dilute acetic

acid, water and 1 N sodium bicarbonate solution, drying and evaporation are effected. The residue is dissolved in diethyl ether and precipitation is effected with petroleum ether. 480 g. of Trit-Gln-(Trit)His-Phe-OMe (melting point 90° with decomposition) are obtained and are dissolved in 1000 ml. of methanol. 50 ml. of hydrazine are added, the mixture is allowed to stand at 20° for 24 hours, concentration is effected to 500 ml., 5 litres of diethyl ether are added, washing with 0.1 N common salt solution, drying, concentrating to 500 ml. and precipitating with petroleum ether are effected. 380 g. of Trit-Gln-(Trit)His-Phe-NHNH₂, having a melting point of 100° with decomposition, $[\alpha]_D^{20} = -12^\circ$ in dimethyl formamide, are obtained.

41 g. of Trit-Gln-(Trit)His-Phe-NHNH₂ are dissolved in 100 ml. of dimethyl formamide and 100 ml. of isopropanol, cooling is effected to -10° and 40 ml. of 4 N hydrochloric acid are added; 9 ml. of 5 N sodium nitrite solution are subsequently added whilst stirring. After 5 minutes 28 ml. of triethylamine and 1000 ml. of ice water are added, filtration is effected with suction, the precipitate is dissolved in ethyl acetate, washing with a saturated common salt solution, drying and evaporating at 0° are effected; the residue is dissolved in 100 ml. of dimethyl formamide, 26 g. of H-Arg-Try-Gly-(CTB)Lys-Pro-OH, 3 AcOH and 4.5 ml. of triethylamine are added, the mixture is allowed to stand at 0° for 16 hours. 1000 ml. of ethyl acetate are added, washing with 0.5 N acetic acid, water and 0.5 N pyridine and evaporation are effected. The residue is dissolved in 100 ml. of ethyl acetate and precipitation is effected with diethyl ether. 46 g. of Trit-Gln-(Trit)His-Phe-Arg-Try-Gly-(CTB)Lys-Pro-OH, having a melting point of 190°, $[\alpha]_D^{20} = -12^\circ$ in dimethyl formamide, are obtained.

The peptide obtained above is dissolved in 200 ml. of pyridine, cooling is effected to -20°, 30 ml. of a 1 N solution of hydrochloric acid in dioxane are added, stirring is effected at -20° for 5 minutes, 7.8 ml. of triethylamine are added, the mixture is concentrated to half its volume, 30 g. of Tri-(trichlorophenyl)-phosphite are added, the mixture is allowed to stand at 20° for 16 hours, is evaporated, the residue is treated with diethyl ether and dissolved in ethyl acetate. Precipitation with diethyl ether, filtration and drying are effected. 51 g. of Trit-Gln-(Trit)His-Phe-Arg-Try-Gly - (CTB)Lys - Pro-OCP.HCl, having a melting point of 180° with decomposition, are obtained.

EXAMPLE 4

D-seryl-L-tyrosyl-L-seryl-L-norleucyl - L - glutaminyl-L-histidyl-L-phenylalanyl - L - arginyl - L - tryptophanyl-glycyl-L-lysyl-L-prolyl-L-valylglycyl-L-lysyl - L - lysyl-L-lysyl-L-lysyl-L-prolyl-L-valyl - L - lysyl - L - valyl-L-tyrosyl-L-prolyl-L-valinamide. (H-D-Ser-Tyr-Ser - Nle-Gln-His-Phe-Arg-Try-Gly-Lys-Pro-Val-Gly - Lys - Lys-Lys-Pro-Val-Lys-Val-Tyr-Pro-Val-NH₂)

6 g. of Trit-Gln-(Trit)His-Phe-Arg - Try - Gly(CTB) Lys-Pro-OCP.HCl and 5.7 g. of H-Val-Gly-(CTB)Lys-(CTB)Lys-(CTB)Lys-Pro - Val - (CTB)Lys-Val-Tyr-Pro-Val-NH₂ are dissolved in 20 ml. of dimethyl formamide, 0.3 g. of imidazole are added and the mixture is allowed to stand at 20° for 3 days. A further 0.6 g. of the same octapeptide hydrochloride are added, the mixture is allowed to stand at 20° for a further 16 hours, precipitation with ethyl acetate and filtration are effected; the precipitate is dissolved in ethanol, the procedure is repeated, precipitation with ethyl acetate, filtration and drying are effected. 8.0 g. of Trit-Gln-(Trit)His-Phe-Arg-Try-Gly-(CTB)Lys-Pro-Val-Gly-(CTB)Lys - (CTB)Lys-(CTB)Lys-Pro-Val-(CTB)Lys-Val-Tyr - Pro-Val-NH₂ (melting point 198° with decomposition, $[\alpha]_D^{20} = -26^\circ$ in dimethyl formamide) are obtained and are dissolved in 200 ml. of acetic acid/water (8:2). The

solution is allowed to stand at 30° for 2 hours, is evaporated, washed with ethyl acetate, filtered and dried. 7 g. of H-Gln-(Trit)His-Phe-Arg-Try-Gly - (CTB)Lys - Pro-Val-Gly-(CTB)Lys-(CTB)Lys - (CTB)Lys - (CTB)Lys-Pro-Val-(CTB)Lys-Val-Tyr-Pro-Val-NH₂ acetate are obtained. 1.0 g. of CTB-D-Ser-Tyr-Ser-Nle-NH-NH₂ is dissolved in 6 ml. of dimethyl formamide, 2 ml. of water are added, cooling is effected to -10°, 1 ml. of 6 N hydrochloric acid and then 140 mg. of sodium nitrite are added, stirring is effected at -5° for 5 minutes, 300 ml. of 0.2 N potassium bicarbonate solution are added and the mixture is centrifuged. The resulting CTB-D-Ser-Tyr-Ser-Nle-N₃ is dissolved in 50 ml. of dimethyl formamide, 5.0 g. of H-Gln-(Trit)His-Phe-Arg-Try-Gly - (CTB)Lys-Pro-Val-Gly-(CTB)Lys-(CTB)Lys - (CTB)Lys - (CTB)Lys-Pro-Val-(CTB)Lys-Val-Tyr-Pro-Val-NH₂ acetate are added, the mixture is allowed to stand at 0° for 12 hours, a further amount of tetrapeptide azide produced from 1.0 g. of CTB-D-Ser-Tyr-Ser-Nle-NHNH₂ is added, the mixture is allowed to stand at 0° for 6 hours, is evaporated, treated with ethyl acetate, washed with hot acetone and ethyl acetate and dried in a vacuum. The resulting product is dissolved in 100 ml. of trifluoroacetic acid, the solution is allowed to stand at 20° in an atmosphere of nitrogen for one hour, is evaporated, treated with ethyl acetate, filtered and dried. The resulting product is dissolved in 500 ml. of 0.2 N acetic acid, the solution is treated with Amberlite IRA-410 in the acetate form, is filtered and lyophilized. After drying over sodium hydroxide 3.5 g. of H-D-Ser-Tyr-Ser-Nle-Gln-His-Phe-Arg-Try-Gly-Lys-Pro-Val-Gly-Lys-Lys - Lys - Pro - Val-Lys-Val-Tyr-Pro-Val-NH₂ acetate, having a homogeneous behaviour in chromatography and electrophoresis, are obtained. (Total hydrolysis gives the following composition of amino acids:

Microanalysis.—Calculated (percent): C, 52.7; H, 7.7; N, 15.3; O, 24.3. Found (percent): C, 52.4; H, 7.8; N, 15.1; O, 24.6. Melting point 204° with decomposition, $[\alpha]_D^{20} = -80^\circ$ in 1 N acetic acid.

What is claimed is:

1. A compound selected from the group consisting of a compound of formula: D-seryl-L-tyrosyl-L-seryl-L-norleucyl-X-L-histidyl-L-phenylalanyl-L-arginyl - L - tryptophanyl-glycyl-L-lysyl-L-prolyl-L-valylglycyl - L - lysyl-L-lysyl-L-lysyl-L-prolyl-L-valyl-L-lysyl - L - valyl-L-tyrosyl-L-prolyl-L-valinamide, in which X is L-glutamyl or L-glutaminyl, and the pharmaceutically acceptable acid addition salts and heavy metal complexes thereof.

2. A compound according to claim 1, in which the compound is D-seryl-L-tyrosyl-L-seryl - L - norleucyl-L-glutamyl-L-histidyl-L-phenylalanyl-L-arginyl - L - tryptophanyl-glycyl-L-lysyl-L-prolyl-L-valyl-glycyl - L - lysyl-L-lysyl-L-lysyl-L-prolyl-L-valyl-L-lysyl - L - valyl-L-tyrosyl-L-prolyl-L-valinamide.

3. A compound according to claim 1, in which the compound is D-seryl-L-tyrosyl-L-seryl - L - norleucyl-L-glutaminyl-L-histidyl-L-phenylalanyl-L-arginyl-L - tryptophanyl-glycyl-L-lysyl-L-prolyl-L-valyl-glycyl - L - lysyl-L-

UNITED STATES PATENT OFFICE
CERTIFICATE OF CORRECTION

Patent No. 3,761,461 Dated September 25, 1973

Inventor(s) Janos PLESS et al.

It is certified that error appears in the above-identified patent and that said Letters Patent are hereby corrected as shown below:

Column 2, line 31, delete "of" and insert
therefor -- or --;

line 50, delete "valyl -- glycyl"
and insert therefor, -- valyl - glycyl --.

Column 3, lines 23-30, delete in entirety.

Column 3, chart, line 2, delete "R" and
insert therefor --R₁ --;

chart, at beginning of all boxes
delete "+" and insert therefor -- minus signs --.

Signed and sealed this 26th day of March 1974.

(SEAL)
